UNITED STATES PATENT OFFICE

2,000,106

PISTON SKIRT EXPANDER

Ralph R. Teetor, Hagerstown, Ind., assignor to
 The Perfect Circle Company, Hagerstown, Ind.,
 a corporation of Indiana

Application January 18, 1933, Serial No. 652,279

10 Claims. (CL 309—12)

My invention relates to means for expanding split skirts of pistons for internal combustion engines and the like.

The principal object of my invention is to provide a simple and novel expander formed of flat spring metal.

Another object of my invention is to provide the expander with novel expansion formations.

Still another object of my invention is to provide an elongated spring expander which is formed of interlocking sections which are readily assembled and easily inserted into a piston skirt.

Further objects and advantages of my invention will appear from the following description taken in conjunction with the accompanying drawing in which:

Figure 1 is a bottom plan view of a piston having one form of my improved expander applied thereto;

Fig. 2 is a perspective view of the expander shown in Fig. 1;

Fig. 3 is a perspective view of a modified form of embodiment of the invention in a two-part expander;

Figs. 4 and 5, respectively, are perspective views of modified forms of the invention as embodied in one-piece expanders; and

Fig. 6 is a fragmentary perspective view of a modified form of joint between two meeting edges of the expander.

Referring to Fig. 1, piston skirt 7 is provided with a vertical slot 8 and piston pin bosses 9 through which extends the usual piston pin 10. The piston may be of any of the well-known types, such, for example, as is shown in my United States Patent No. 1,885,038, issued October 25, 1932. In most pistons formed of aluminum or the like, the head is wholly or partially separated from the skirt by a circumferential slot or slots 40 and the skirt is provided with a vertical slot to permit it to expand and contract. It is in this general type of piston that my invention is peculiarly adapted for use.

The expander illustrated in Figs. 1 and 2 comprises two complementary and similar half-sections 12 and 13 formed from flat spring metal. The end edges 14 of the parallel sides of the sections abut and have laterally displaced interlocking lugs 12^a and 13^b. It will be observed by referring to Fig. 1, that when the expander is assembled and mounted in the skirt of the piston, the parallel sides of the expander press against the facing ends of the piston pin bosses 9 and the piston pin 10 then projects through the openings 55 15 (Fig. 2) in the sides of the expander. Each

end of the expander contacts with the piston skirt as at the points 16. The expander is also provided with S-shaped or double expansion folds or formations 17 which include the points 16. The sides of the expander adjacent the pin bosses 9 are preferably provided with vertical folds 18 and the portions 19 of the expander between the adjacent pairs of folds 16 and 18 are preferably semi-circular.

When the expander is to be applied to the skirt, the two half sections are brought together with their lugs 12^a and 13^b interlocking; the expander is compressed or contracted lengthwise and crosswise and while in this condition it is inserted into the skirt, and it is then released. With the expander in position, it will be apparent that its sides press firmly in opposite directions against the bosses 9 and that the points 16 press firmly against the interior of the piston skirt. Thus the expander tends to expand the cylinder so that it at all times snugly fits the cylinder wall. The expansion folds afford the desired action in accomplishing this result.

The expander is particularly useful in worn pistons though it is susceptible of use in new pistons.

In the modified form of embodiment shown in Fig. 3, the two half sections 12 and 13 are formed somewhat differently from the sections of the first form shown in Figs. 1 and 2, in that in the form shown in Fig. 3, each half has one complete side and the edges abut at either side of the piston pin and not in the vertical plane containing the axis of the piston pin as in the first form. In Fig. 3, one edge of each section has an overlying flange 22 provided with openings 23 into which extend locking lugs 24 on the adjacent edge of the other section.

In the form illustrated in Fig. 4, the expander is of the same general shape as those shown in Figs. 1, 2 and 3 but, in the Fig. 4 form, the expander is made from a continuous strip, one edge of which is bent to provide a channel 25 in which the other edge is seated. The latter edge is also provided with two lugs 26 extending through openings in the channel 25.

Fig. 6 illustrates a form of joint comprising a channel 27 in one edge to receive the other edge, the latter having two lugs 27^a extending over and below the ends of the channel.

Fig. 5 shows an expander which is similar in general contour to those shown in the other figures but which is formed from a tube or a continuous band so that it is endless and has no joints.

It will be apparent from the foregoing that an expander embodying my invention is simple in structure, cheap to manufacture, easy to assemble and efficient in use. Further modifications may be indulged in without departing from the spirit of the invention.

I claim:

1. A one-piece piston skirt expander formed of flat spring metal and forming a continuous integral oblong figure having a plurality of spaced apart expansion folds adjacent each end.
2. A piston skirt expander comprising two complementary sections having their end edges abutting and provided with interlocking means at said edges and with expandible formations.
3. A piston skirt expander formed of flat spring metal and generally oblong in shape, the expander being split forming end edges the end edges abutting and interlocking, and the expander having expandible formations.
4. A piston skirt expander formed of two spring metal sections, and generally oblong in shape, with the sides provided with openings to receive a piston pin, the edges of the two sections abutting in a vertical plane containing the centers of said openings.
5. A piston skirt expander formed of two spring metal sections, each generally U-shaped and having spaced expansion folds, the end edges of the two sections having interlocking projections.
6. In combination with a piston having a split skirt, an expander formed of spring metal and generally oblong in shape and contacting with the piston skirt at spaced points intermediate the pin bosses, the expander having reverse expansion folds including each of said points.
7. In combination with a piston having a split skirt and piston pin bosses, an expander comprising two U-shaped sections having their end edges abutting and provided with interlocking means, the sides of the expander engaging said bosses and pressing outwardly thereagainst and each section of the expander being provided with reverse expansion folds intermediate its ends.
8. In combination with a piston having a split skirt and piston pin bosses, an expander formed of flat spring metal and generally oblong in shape and having parallel sides adapted to press against the facing edges of said bosses, the ends of the expander being adapted to engage the piston skirt intermediate the bosses and each side of the expander having vertical yielding formations adjacent the pin bosses.
9. A piston skirt expander formed of flat spring metal and generally oblong in shape and of closed configuration and having S-shaped formations including the points at which the expander engages the skirt.
10. A piston skirt expander of generally oblong shape and closed configuration and comprising two complementary sections with means for interlocking their ends together.

RALPH R. TEETOR.
